UNITED STATES PATENT OFFICE.

SAMUEL ROSENBAUM AND BENATT FINKELSTEIN, OF LOS ANGELES, CALIFORNIA.

ADJUSTABLE SLEEVE-PROTECTOR.

1,141,656.

Specification of Letters Patent. Patented June 1, 1915.

Application filed August 19, 1913. Serial No. 785,498.

To all whom it may concern:

Be it known that we, SAMUEL ROSENBAUM and BENATT FINKELSTEIN, both citizens of the United States, residing at Los Angeles, 5 in the county of Los Angeles, State of California, have invented new and useful Improvements in Adjustable Sleeve-Protectors, of which the following is a specification.

This invention relates to sleeve protectors, 10 and the principal object is to provide a sleeve protector with means for adjustably securing the same in relation to the sleeves of a garment.

It is also an object to provide a sleeve pro- 15 tector with elastic securing means.

It is a still further object to provide a sleeve protector with an elastically mounted strap provided with a toothed hook by which the latter may be inserted within the band of 20 the protector.

In the drawings accompanying this specification and forming therewith the application for Letters Patent: Figure 1 is an elevation of the sleeve protector with the invention applied thereto, showing the upper end 25 of the protector in its unsecured position.

Fig. 2 is a view of the upper portion showing the hook engaged in locked position. Fig. 3 is a detail of the method of adjusting 30 the cuff.

More specifically in the drawings, 5 designates a sleeve protector formed of fabric of the usual configuration having a cuff portion 6 and a large portion 7 adapted to fit 35 over the elbow, and an upper end which is preferably reinforced with a tape 8 entirely around the margin thereof and on the outer side of the fabric. Secured to the point 9 is an elastic band 10 or ribbon which 40 passes through a loop 11 secured to a short tape 12 which is fastened to the tape 8 previously mentioned, this loop being in such relation to a hook 14 that there will be a certain amount of fold or fullness of the ma-

terial intermediate of the bands 9 and the 45 point where the loop strap is secured.

The hook is provided with a plurality of teeth 15 which are preferably pointed and so arranged that they may readily engage within the tape 8, this hook being preferably 50 formed of the rectangular configuration shown and clamped to the sides of the elastic by means of suitable tongues 16.

The cuff portion is formed with a division preferably formed at the line of a seam, and 55 the opening provided for this is preferably closed by a gusset 20 so that when the elongated portion 21 of the cuff provided with the cupped member 22 of the clamping member 23 are secured the protector will be en- 60 tirely closed in and the sleeve of the wearer will be completely protected.

The operation of the adjustable closure for the upper portion will be readily understood, the elastic forming a band 10 within 65 which the loop 11 is freely movable and allows sufficient resiliency to hold the protector in proper relation, as well as providing free movement of the wearer's arm.

What we claim is:

A sleeve protector, comprising a fabric body member, a continuous non-elastic band of tape on one end of said body member, an elastic band secured to said tape and extending parallel therewith, a metallic loop on the 75 tape spaced from the connection between the tape and the elastic band through which said elastic band passes, and a hook mounted on the end of the elastic band adapted to engage with the non-elastic tape. 80

In witness that we claim the foregoing we have hereunto subscribed our names this 9th day of August, 1913.

SAMUEL ROSENBAUM.
BENATT FINKELSTEIN.
